UNITED STATES PATENT OFFICE.

BYRON M. GUNSTON, OF OSWEGO, NEW YORK, ASSIGNOR TO THOMSON KINGSFORD, OF SAME PLACE.

BOX-NAILING MACHINE.

SPECIFICATION forming part of Letters Patent No. 481,863, dated August 30, 1892.

Application filed March 5, 1892. Serial No. 423,900. (No model.)

To all whom it may concern:

Be it known that I, BYRON M. GUNSTON, a citizen of the United States, residing at Oswego, in the county of Oswego and State of New York, have invented certain new and useful Improvements in Box-Nailing Machines, of which the following is a specification.

My present invention relates to that part of nailings-machines which delivers the nails from a pan or receptacle separately in proper position to be operated upon by the hammer mechanism.

The object of my invention is to render the mechanism entirely automatic and to so organize the apparatus that nails may be fed to the hammers or punches evenly, regularly, and without clogging the moving parts.

In the accompanying drawings, Figure 1 is a plan view of a nail-feeding machine embodying my improvements. Fig. 2 is a vertical section on the line 22 of Fig. 1. Fig. 2^a is a detail view showing the connection of the pan-operating mechanism with the hammer cross-head. Fig. 3 is a vertical section on the line 33 of Fig. 1. Fig. 4 is a similar section showing the oscillating nail-track in its elevated position. Figs. 5 to 10, inclusive, are on an enlarged scale. Figs. 5 and 6 are detail plan views showing particularly the cut-off mechanism. Fig. 7 is another detail view of the cut-off mechanism. Fig. 8 is a vertical transverse section on the line 88 of Fig. 1. Fig. 9 is a detail view in section on the line 99 of Fig. 4. Fig. 10 is a perspective view of part of the casing of the cut-off mechanism.

The frame A may be of any construction suitable to support the different parts of the mechanism.

The pan or receptacle B, into which the nails are dumped in a miscellaneous mass, is provided at its rear lower end with pivots b, journaled in standards a, adjustably secured to the frame A by means of set-screws a', extending through slots b' in the standards a. The nail-pan is divided by a transversely-arranged partition B', the lower end of which is located a short distance above the bottom. That portion of the pan in front of the partition B' is divided, as shown in Fig. 1, into compartments C C', &c., by partitions c, which,

as shown, are pivotally connected to the bottom of the pan by screws c' at their front ends. The rear ends of the partitions c are provided with screws c², extending through slots c³ in the partition B', and these screws carry clamping-nuts c⁴. By this means the partitions c may be set at different angles, and thus the quantity of nails delivered to the different compartments may be varied.

As before stated, the rear end of the nail-pan may be adjusted vertically by means of its adjustable standards a, and by this means the inclination of the pan may be varied to regulate the quantity of nails fed from it. The front end of the pan is supported on springs d, surrounding bolts D, extending through a cross-piece A', mounted on a bracket A² of the frame. The springs d project a short distance upwardly from the bolts and rest on the cross-piece A'. The lower ends of the bolts are provided with adjusting-nuts d², by means of which the bolts may be adjusted vertically toward and from the upper ends of the springs. Any desired number of these supporting devices may be employed.

The nail-pan is operated by a rod E, carrying at its upper end a spring e, which may be adjusted by means of nuts e'. The lower end of the rod is connected to an angle-iron F, secured to the cross-head F' of the hammer-actuating mechanism. The arrangement is such that as the hammer-actuating mechanism is reciprocated vertically the rod E is reciprocated and imparts a vertical oscillation or vibration to the nail-pan. The vibration of the pan may be regulated by adjusting the connection of the rod E with the angle-iron F. It will thus be seen that I have provided various ways for regulating the supply of nails from the pan. First, the vertical adjustment at the rear end of the pan; second, the adjustments of the supports D; third, the adjustment of the spring e of the rod E, and, fourth, the adjustment of the connection of the rod E with the angle-iron F.

It will be understood that if the springs d project only a short distance above the bolts D the pan B as it descends will strike the bolts with greater force than if the springs project a greater distance above the ends of

the bolts. These several devices may be nicely adjusted or regulated to supply the nails at the desired speed, and the quantity of nails fed through the different subdivisions 5 of the nail-pan may, as before explained, be regulated by adjusting the partitions *c*. It will be understood that the springs *d* tend to continue the vibration of the pan, and thus tend to shake the nails down the incline should 10 they tend to stop.

In front of and below the nail-pan is a hopper *G*, supported on the bracket *A*² of the frame and corresponding in width to the width of the nail-pan and having its bottom 15 subdivided into a series of V-shaped troughs *g*, corresponding with the subdivisions of the nail-pan. These troughs may be formed in any suitable way with sloping sides inclining from their upper ends downwardly, and preferably at the lower ends of the troughs I arrange blocks *G*', which tend to guide the nails to the bottoms of the troughs and prevent their lodging against the front end of the hopper or from finding their way out of the hopper, except in the manner hereinafter described.

Retarding devices for preventing the nails from being delivered too rapidly to the hopper or for preventing them from jumping to 30 the lower end of the hopper are mounted immediately in front of the pan on vertically-adjustable standards *H*. The standards are connected by a shaft *h*, on which are pivoted a series of retarders *H*', each shown as consisting of a plate *h*', which when the retarding device is in its normal position is inclined from the shaft *h* downwardly to the trough, on which it rests, as shown in Fig. 8.

A plate *h*² projects upwardly and rearwardly 40 from the shaft *h* and deflects any nails that might tend to jump over the shaft onto the plate *h*'. The plate *h*' is suitably shaped, as shown in Fig. 8, to conform to the bottom of the trough on which it rests.

45 The retarding devices at the ends of the hopper are provided with end pieces *h*³, which will prevent the nails from falling out at the sides of the hopper or pan. The retarding devices may be mounted on the shaft *h* in any suitable way. I have shown in the drawings a convenient way for securing them, which consists in cutting away the ends of the plates *h*² and turning these ends around the shaft; but other securing devices may be 55 employed.

The retarding devices may be adjusted to any desired angle by the vertical adjustment of the standards *H*, and the nails as they are delivered from the nail-pan are deflected to 60 the upper ends of the troughs, so that they are made to traverse practically the entire length of the trough, instead of going immediately to the lower ends. The bottoms of the several troughs are slotted from end to 65 end to permit the oscillating nail-tracks *I* to reciprocate vertically through them. These nail-tracks are slotted longitudinally at *i* and

are beveled at *i*' from their outer edges inwardly toward the slots, being thus adapted to guide the nails to the slots, into which they fall with their points downward, and are suspended therein by their heads. The width of the slots for different sizes of nails may be varied in different ways—for instance, by employing a removable piece *i*² at one side of the slot.

The oscillating nail-tracks are mounted on a shaft *J*, supported in the main frame in any suitable way, and may be held in place by collars. The front ends of the tracks carry 80 curved guard-plates *I*', which reciprocate vertically between the end blocks *G*' and serve to prevent nails from falling out in front of the oscillating tracks while they are being operated. Each track is actuated by means of a rod *K*, secured to a bracket *K*', adjustable by means of set-screws *k*', working in slots *k*². The lower end of the rod *K* is connected to the angle-iron *F* of the hammer-actuating cross-head *F*'. Between a nut *k*³ 90 on the rod and the angle-iron is interposed a spring *k*⁴, and the lower end of the rod beyond the angle-iron carries a nut *k*⁵. As the cross-head *F*' is reciprocated vertically, a vertical oscillation is imparted to all the tracks. 95 The yielding connections between the angle-iron and the rods *K* are for the purpose of preventing a strain on the mechanism should the cut-off devices become clogged, as will be hereinafter explained. The upper rear ends 100 of the oscillating tracks connect with stationary tracks *L*, which incline downwardly from their front ends to the cut-off devices. The connection between the movable track and the stationary track is such as to provide a close joint at all times, the front face of the stationary track being curved to correspond with the curved rear end of the movable track, as clearly shown in Fig. 2. The oscillating tracks are provided with heels *I*², 110 which abut against the under sides of the stationary tracks. Thus the downward movement of the tracks is limited, and when at their lowermost position the tracks proper or nail-receiving portions thereof are inclined, 115 as shown in Fig. 2, to permit the nails to slide downwardly over them by the force of gravity. The stationary tracks *L* project a short distance beyond the rear end of the hopper and into the slotted troughs thereof. It is 120 therefore necessary to close the slots immediately above the front ends of the stationary tracks. To do this, I employ hinged gates *M*, which rest by gravity at their lower front ends on the front ends of the stationary tracks 125 when the oscillating tracks are depressed, but which are raised by the oscillating tracks when they are elevated. The front ends of the gates are notched at *m* to permit the heads of the nails to pass when the tracks *I* are elevated 130 and the nails are sliding downwardly therefrom. The depth of the slots in the tracks is a little greater than the length of the nails; but when the nails are suspended by their

heads they are free to move without touching bottom. Headless nails fall through the slots and pass out at α into any suitable receptacle.

5 The cut-off devices N are located at the lower rear ends of the stationary tracks. There is a cut-off for each one of the tracks. As the cut-off devices, which I employ are all alike, the description of one of them will be sufficient. A base-piece O is employed for carrying the cut-off mechanism of all the tracks. This base-piece is provided with upright boards O', grooved at o to receive the upright removable board p, to which the top or 15 cover P is secured. The cover and its vertical board p, in connection with the uprights O', constitute a casing for the cut-off mechanism, and as the covers may be readily removed the cut-off mechanism may be easily 20 gotten at and repaired, if necessary.

The cut-off devices for each track are shown as consisting of a finger Q, carried by a transversely-sliding block Q', pressed in one direction by a spring q, held in place by a stud q' on 25 one of the uprights O'. The finger may be adjusted by means of the screw q², which secures it to the block Q'. The block is moved transversely against the force of the spring q by means of an inclined bar R, pivotally connected to the oscillating track I. The rear end of the bar engages an inclined end of the block Q', and it works through a suitably-shaped opening p' in the upright p and against one of the vertical boards O'. The 30 block is formed on its front side with a recess q³, arranged immediately over an opening o in the cross-piece O, beneath which is arranged a tube S, which may communicate with tubes or devices which carry the nails 35 to the hammer. The finger Q is formed with an enlargement y, which projects rearwardly a short distance into the recess q³. This enlargement gradually merges into the point or edge of the finger, and as the finger is reciprocated the nail, which is separated from the others in the track, is moved backwardly into the recess over the opening o, through which it falls into the tube S. The finger reciprocates transversely through a recess l in the rear 40 end of the track, and the track immediately in front of the finger is provided with inclined diverging edges l'. Each track is cut away at l' between its upper and lower ends and immediately below this cut-away portion is perforated at T. The track immediately above the 45 perforation T overhangs the perforation to a slight extent, as shown in Fig. 4. As the nails are fed down the track they jump across the perforation T to the lower end of the track and stop close to the fingers or cut-offs; but should more than enough nails be supplied to the lower end of the track and should they fill the track from the fingers or cut-offs to the perforation T the nails subsequently fed down 50 the track will fall through the perforation

into a receptacle provided therefor. By this means the clogging of the tracks is prevented. Most of the nails are fed down the track in regular order, suspended by their heads. Occasionally, however, nails will pass the gate 70 without assuming a vertical position or being suspended by their heads. Should this be case, they will fall from the tracks over the inclines l' before reaching the cut-off devices. The width of the slot in each stationary track 75 may be made adjustable by means of a removable side piece L', corresponding with the removable side piece l² in the oscillating track, thus allowing nails of different sizes to be used. 80

The operation of the mechanism has been indicated in describing its construction. Briefly stated, the operation is as follows: The nails are dumped in a miscellaneous mass into the rear end of the nail-pan, and as the 85 nail-pan is oscillated or vibrated the nails are fed downwardly against the deflectors or retarders, which deliver them to the upper ends of the troughs in the hopper G. The nails slide down the troughs and are deflected into 90 the slots i in the upper ends or edges of the tracks I. Defective nails fall through the slots and out through the openings α . A portion of the perfect nails are suspended by their heads in the tracks when the tracks are 95 in their lowermost position, and as the tracks are raised those nails which are not suspended by their heads pass to the sides of the tracks until the track falls again, while the nails in the slots pass by the gates M onto 100 the inclined stationary tracks L, down which they slide, jumping the openings T, and are arrested at the cut-off devices. As the cut-off knives are oscillated the nails are picked off separately and delivered through openings o and tubes S. When the knives are withdrawn, the lowermost nail rests against the block Q', as shown in Fig. 5, and as the knife moves across the path of the track it separates the lowermost nail from the others 105 and delivers it through the opening o. The mechanism is so timed and operated that the nail-pan is intermittently vibrated and the oscillating nail-tracks are simultaneously actuated. 110

The cut-off devices are operated from the oscillating nail-tracks, and the connection between the nail-tracks and the reciprocating cross-head of the hammer is yielding, as before described, so that should the cut-off 120 mechanism become clogged there is no undue strain which would tend to break any parts of the apparatus. 115

I claim as my invention—

1. The nail-pan herein described, provided with partitions pivoted at their lower ends and having devices at their front ends for securing them in the desired adjusted positions. 125
2. The nail-pan herein described, provided with partitions pivoted at their lower ends to 130

- the bottom of the pan and adjustably secured at their upper rear ends to a slotted cross-piece, substantially as described.
3. The combination of the nail-pan, the bolts carrying springs, on which the nail-pan is supported at its front end, and means for vibrating the pan.
4. The combination of the nail-pan, the bolts carrying springs, on which the nail-pan is supported, and the vertically-reciprocating rod carrying a spring at its upper end, bearing against the nail-pan.
5. The combination of an inclined nail-pan, means for oscillating it vertically, an inclined hopper in front of and below the nail-pan, and adjustable retarders interposed between the hopper and the pan to deflect the nails to the upper end of the inclined bottom of the hopper.
6. The combination of the nail-pan, the hopper, the retarders having the downwardly and rearwardly inclined plates and the upwardly and rearwardly inclined plates, and a shaft on which the plates are mounted.
7. The combination of a nail-pan, a hopper having a forwardly and downwardly inclined bottom and located below the nail-pan and in front thereof, the oscillating nail-tracks working vertically through the hopper and inclined forwardly and downwardly at the end of the downward stroke, the stationary nail-tracks, with which the oscillating rearwardly-extending downwardly-inclined nail-tracks connect, and cut-off mechanism at the lower ends of the stationary tracks.
8. The combination of the hopper, a V-shaped trough therein, the oscillating track working vertically through the trough, and the hinged gate notched at its lower end and bearing on both tracks and which is raised and lowered by the oscillating track.
9. The combination of a hopper having an inclined bottom, a vertically-oscillating track therein, and a guard-plate I', carried by the lower end of the track and extending upwardly therefrom, for the purpose specified.
10. The combination, substantially as set forth, of an inclined hopper provided with a series of V-shaped troughs, an oscillating track, the inclined blocks at the lower ends of the hopper on opposite sides of the track, the upwardly-projecting guard-plate I' be-
- tween the blocks, and the gate hinged to the upper end of the hopper and bearing against the track.
11. The inclined stationary track herein described, having the opening T, through which superfluous nails are delivered, connected at its upper end with means for feeding nails to the cut-off mechanism, in combination with cut-off mechanism at the lower end of the track, having devices for supporting a number of nails between the opening T and the lower end of the track, and a finger for picking off one nail at a time from the nails thus supported, substantially as set forth.
12. The combination, substantially as set forth, of the stationary track, the oscillating track, means for operating the oscillating track, the transversely-reciprocating spring-pressed block carrying the cut-off finger, and connections between the oscillating track and the spring-pressed block for moving the block against the force of the spring.
13. The combination of the finger-carrying spring-pressed block, the grooved uprights, between which the block is mounted, and the top piece or cover provided with an upright board working vertically in the grooves.
14. The combination, with the vertically-reciprocating cross-head, of cut-off devices, the vertically-oscillating track, connections between the track and the cut-off devices, by which the latter are operated, a rod adjustably secured to the track, and a yielding connection between the rod and the cross-head.
15. The combination of the hinged nail-pan, the hopper, the oscillating tracks extending into the hopper, the stationary tracks, the cut-off mechanism, the hammer-carrying cross-head, a rod adjustably connected thereto for oscillating or vibrating the nail-pan, connections between the oscillating nail-tracks and the cut-off mechanism, rods connecting the oscillating nail-tracks with the hammer-carrying cross-head, and springs carried by the lower ends of the rods.

In testimony whereof I have hereunto subscribed my name.
